UNITED STATES PATENT OFFICE.

JAMES HEYWOOD, OF PHILADELPHIA, PENNSYLVANIA.

DESIGN FOR A CHANNEL-BAR SUPPORT.

SPECIFICATION forming part of Design No. 31,551, dated September 26, 1899.

Application filed August 28, 1899. Serial No. 728,793. Term of patent 7 years.

To all whom it may concern:

Be it known that I, JAMES HEYWOOD, a citizen of the United States, residing at the city of Philadelphia, in the county of Philadelphia and State of Pennsylvania, have invented and produced a new and original Design for a Channel-Bar Support, of which the following is a specification, reference being had to the accompanying drawings, forming part hereof, in which—

Figure 1 is a perspective view of a channel-bar support of the design of my invention, and Fig. 2 is a transverse sectional view of the same.

The leading feature of my design consists of the shape or configuration and openings of the channel-bar support.

Referring to the drawings, A represents the design, having a rectangular-shaped face a, with circular openings a', which merge into

oblong straight-sided openings a², and these openings are arranged at suitable distances apart in and extending through the body or face of the support of the said design. The face or body of the support of the said design has two rear tapering projecting walls b and b', as clearly illustrated in Fig. 2 of the drawings.

Having thus described my invention, what I claim as new, and desire to secure by Letters Patent, is—

The design for a channel-bar support, substantially as shown and described.

In testimony whereof I have hereunto set my signature in the presence of two subscribing witnesses.

JAS. HEYWOOD.

Witnesses:

J. WALTER DOUGLASS,
THOMAS M. SMITH.
